UNITED STATES PATENT OFFICE.

SIDNEY M. WEATHERLY, OF NEW YORK, N. Y.

BLOCK OR BASE FOR HOLDING PLATES FROM WHICH PRINTED IMPRESSIONS MAY BE TAKEN.

SPECIFICATION forming part of Letters Patent No. 695,977, dated March 25, 1902.

Application filed September 11, 1900. Serial No. 29,691. (No model.)

To all whom it may concern:

Be it known that I, SIDNEY M. WEATHERLY, a citizen of the United States, residing at New York, in the county of New York and State 5 of New York, have invented a new and useful Improvement in Blocks or Bases for Holding Plates from Which Printed Impressions May be Taken, of which the following is a specification.

10 The object of my invention is to furnish a base for supporting and holding stereotype, electrotype, and other plates from which printed impressions may be taken that will permit of said block being extended or contracted in all directions, whereby it may support and hold and be fitted to plates of different sizes.

15 My invention consists in certain features and parts and combinations of features and parts, as herein described.

In the accompanying drawings, Figure 1 represents in plan one embodiment of my invention in which four corner-pieces of the printer's block are brought together at their 25 inner edges to form a base for supporting a small plate from which printed impressions may be taken. Fig. 2 is a similar view of a slightly-larger base, showing the four corners extended by an interposed cross formed of 30 one longitudinal and two transverse strips. Fig. 3 illustrates in plan the interposed strips of the size used in Fig. 2, but showing the cross-strip in one piece and two longitudinally-extending strips. Fig. 4 shows similar 35 views of strips, but of slightly-larger size than those shown in Fig. 3. Fig. 5 illustrates a cross-section as taken on the line 5 5 of Fig. 1. Fig. 6 is a similar view to Fig. 2, but showing the interposed material in the form 40 of an integral cross. Fig. 7 is a detail in plan of the integral cross shown in Fig. 6. Fig. 8 is a similar view of a cross-shaped piece having slightly-wider arms than the one shown in Figs. 6 and 7.

45 Similar letters represent like parts in all the figures.

A, B, C, and D represent four corner-pieces of my improved extension or expansible printer's block or base. On one side and one end 50 of the block—as, for example, on the outer side edges of the blocks B D and on the end edges of the blocks C D—are plates provided

with hooked flanges *a*, the hooked portions of said flanges overlapping the faces of the blocks B, D, and C. On the opposite sides 55 or edges of the block or base to the hooked flanges *a* are adjustable hooks *b*, each hook forming part of the sleeve *c*, through which passes a rotatable screw *d*, which has no longitudinal movement. The sleeve *c* is inclosed 60 and guided in a cut-away portion *e* in the block. A wheel *f*, secured to the screw *d*, provides means for turning said screw. The flanges *a* and the adjustable hook *b* constitute 65 opposing members for clamping a plate on the base or block. The top of the block or base is provided with recesses or grooves *g*, extending, respectively, on either side of the wheels *f*, and I prefer to have an outer wall 70 *h* for said recess on the corner-pieces A B C D, as shown in the drawings. The upper portion of the periphery of said wheel extends a little above the bottom of the groove 75 *g*, and said periphery is toothed to form a ratchet. This construction enables the wheel *f* to be more easily turned by means of a rack-piece (not shown) engaging with the teeth of the wheel *f*, the groove *g* serving to retain and guide said rack and prevent its slipping off the wheels and of running the 80 risk of damaging the plate. The bottom of the groove *g*, which is integral with the block, constitutes the track for said rack. The rotation of said wheel, and consequently the rotation of the screw, serves to adjust the 85 sleeve *c*, with its hook *b*, longitudinally on said screw. The stereotype, electrotype, or other plate that is to be held on the base or block has two of its edges inserted under the hooked flanges *a*. Then the hooks *b* are adjusted along the screw *d*, so as to clamp the 90 edges of the plate opposite to the hooks *a*, when the plate will be held firmly in place.

E and E' are strips or cross-pieces to be inserted between the inner ends of the pieces 95 A B C D to increase the length of the plate-holder or base, and F F' are other strips for insertion between the inner edges of the pieces A B C D to increase the width of the plate-holder. (See Fig. 2.) In said figure I 100 have shown two strips E and one strip F to the plate-holder. It will be seen that the strips when properly inserted between the corner-pieces form a cross, and this cross may

be made in one or more parts, as desired, so long as it serves to be inserted between the inner edges of the pieces A B C D to extend the area of the plate-holder or block 5 in both directions. That part of the upper surface of the cross in line with the depression *g* is on the same plane with the bottom of said groove to permit the movement back and forth of the rack-piece above referred to 10 on all of said wheels. I have shown in the drawings the cross recessed or cut away, as at *i*, the surface of such part being in the same plane with the bottom of the groove or recess *g* and the recess *i* having no outer 15 boundary-walls that would be likely to break off, and thus leave a rough or ragged track for the rack-piece. In Figs. 6, 7, and 8 I have shown the cross as integral. The cross G in Fig. 7 has narrow arms, so as to extend 20 the base or holder only slightly, as shown in Fig. 6, and the cross G, Fig. 8, has wider arms, so as to make a base of greater area than that shown in Fig. 6. When either of the arms of the cross G is quite wide, it will 25 be evident that the ends of said arms may be provided with clamp *a b*, so as to better hold a large plate.

From the above it will be seen that a plate-holder or base with just the usual parts of an 30 unextended holder may be readily extended or contracted to any desired size and with a comparatively small number of plane extending strips.

My improved base or block may be made 35 of wood, iron, or any other suitable material.

Of course it is also evident that certain details of my extension block or base may be varied without departing from my invention.

The entire block or base, including the 40 interposing strips or pieces, is adapted to be held together in the chase or frame used on printing-presses by the furniture of the chase in a manner well known in the art.

What I claim as new, and desire to secure 45 by Letters Patent, is—

1. A block or base for holding a plate from which printed impressions may be taken,

said block or base having four separable corners, all constructed to be brought together, an interposed strip or strips extending in four 50 different directions from a center and separating all of said corner-pieces from each other, and said block provided with opposing clamping members, extending above its upper surface, one of such members having 55 means for adjusting it relative to its opposing member, the tops of the corner-pieces provided with a recessed track on either side of the operating means for the adjustable member, and two of the diverging interposed 60 strips between the corner-pieces provided with recesses on their ends having no outward boundary-walls, and the bottoms of said recesses forming continuations of the tracks in the corner-pieces, all substantially as and for 65 the purposes set forth.

2. A block or base for holding a plate from which printed impressions may be taken, said block or base having four separable corners, all constructed to be brought together, 70 an integral interposed strip or strips extending in four different directions from a center and separating all of said corner-pieces from each other, and said block provided with opposing clamping members, extending above 75 its upper surface, one of such members having means for adjusting it relative to its opposing member, the tops of the corner-pieces provided with a recessed track on either side of the operating means for the adjustable member, and two of the diverging interposed 80 strips between the corner-pieces provided with recesses on their ends having no outward boundary-walls, and the bottoms of said recesses forming continuations of the tracks in 85 the corner-pieces, all substantially as and for the purposes set forth.

In testimony whereof I have signed my name to this specification in the presence of two subscribing witnesses.

SIDNEY M. WEATHERLY.
